UNITED STATES PATENT OFFICE.

JOHN H. FREEMAN, OF SAVANNA, ILLINOIS.

TOILET VESSEL.

No. 878,625.

Specification of Letters Patent.

Patented Feb. 11, 1908.

Application filed November 17, 1905. Serial No. 287,894.

To all whom it may concern:

Be it known that I, JOHN H. FREEMAN, a citizen of the United States, residing at Savanna, in the county of Carroll and State of Illinois, have invented a new and useful Toilet Vessel, of which the following is a specification.

This invention relates to toilet vessels.

The objects of the invention are in a novel and practical manner to obviate noise when the cover of the vessel is removed or replaced; to secure an effective seal between the vessel and the cover, thereby to preclude the escape of odors; and to prevent scratching or cutting of the skin of the user of the vessel should the mouth or rim thereof be chipped or nicked.

With the above and other objects in view, as will appear as the nature of the invention is better understood, the same consists in the novel form of toilet vessel seal and cushion, as will be hereinafter fully described and claimed.

In the accompanying drawings forming a part of this specification, and in which like characters of reference indicate corresponding parts: Figure 1 is a view in section through the cover and upper portion of the vessel showing the improvements applied thereto. Fig. 2 is a similar view of the upper portion of the vessel, the cover being removed. Fig. 3 is a perspective detail view of the seal and cushion forming the subject matter of the present invention.

Referring to the drawings, V designates the upper portion of an ordinary toilet vessel having the usual outward projecting marginal rim R, and C the cover having the usual downward projecting annular flange F, and as these parts may be of the ordinary and common construction, further description is deemed unnecessary.

The present invention resides in a novel attachment to be used in conjunction with the vessel to form a combined seal, muffler and cushion.

The attachment embodies a band of rubber 1 the edges of which are provided with reinforces 2 and 3, that are formed, in this instance, by folding over the margins of the band and cementing them to the body thereof. While this will generally be the pre-

ferred manner of reinforcing the attachment, it is to be understood that the same results can be secured by forming the band with thickened edges, or by cementing strips along the edges, and as this will readily be understood, detailed illustration of such obvious modifications is omitted.

The band is of less circumference than the rim R, thereby necessitating its being stretched when placed in position, and when combined with the rim, will by frictional contact therewith be firmly held in place. The band will extend inward, in a horizontal plane, beyond the inner edge of the rim a sufficient distance to cause it to contact with the flange F, so that when the cover is positioned, the flange will project through the openings or annulus formed by the inward projecting portion of the band and thereby form an effective seal for the purpose, that portion of the band resting upon the upper face of the rim subserving the function of a cushion and protector.

It will be noted by reference to Fig. 1 that when the cover is positioned that the reinforce bears directly against the flange and is deflected from a horizontal plane thereby, and as the reinforce will present greater resistance to stretching than the remainder of the band, it will be seen that the union between it and the flange will be a positive one.

The reinforce 3 will lie under the outer surface of the rim, and thereby operate to hold the device in position.

The attachment is thoroughly sanitary, may be removed and replaced at will, and will be found in an efficient and practical manner to secure the objects sought.

I claim:

A vessel comprising a body of inflexible material having at its upper edge an outstanding annular flange, a reversible cushion, seal, and dam for the same comprising a cylinder ring of elastic nonabsorbent material which is relatively thickest at its edges by being bent back upon itself, said ring resting at its thinner part over the edge of the flange of the body and being thereby distorted so that its upper portion is held in a horizontal plane extending in from the upper edge of the vessel and forming a

cushion for the edge of the vessel and a seal and dam for the contents thereof, and a cover having a depending annular flange between which and the inner side of the vessel, the inner thickened edge of the ring lies.

In testimony that I claim the foregoing as

my own, I have hereto affixed my signature in the presence of two witnesses.

JOHN H. FREEMAN.
